JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR END PLATE.

1,122,450.

Specification of Letters Patent. Patented Dec. 29, 1914.

Application filed September 30, 1914. Serial No. 864,296.

To all whom it may concern:

Be it known that I, JACOB H. WEISBROD, residing at St. Louis, Missouri, and being a citizen of the United States, have invented 5 certain new and useful Improvements in Car End Plates, of which the following is a full, clear, and exact description, such as will enable others skilled in the art to which it appertains to make and to use the same, 10 reference being had to the accompanying drawings, which illustrate the preferred form of the invention, though it is to be understood that the invention is not limited to the exact details of construction shown 15 and described, as it is obvious that various modifications thereof will occur to persons skilled in the art.

In said drawings: Figure 1 is an end elevation of the upper portion of a railway car, and illustrates the incorporation therein 20 of my improved end plate. Fig. 2 is a horizontal section taken on line 2—2 of Fig. 1, looking in the direction of the arrows, and shows approximately one-half of the end 25 plate in inverted plan. Fig. 3 is a fragmentary side elevation of an upper corner of the car structure shown in Fig. 1; and Fig. 4 is a fragmentary central longitudinal section of the end portion of the car 30 structure, being taken on line 4—4 of Fig. 1.

My present invention relates to end plates forming parts of the super-structure framing of railway cars, and an object is to provide an end plate so formed that it will be 35 adapted to afford a support for certain roof-frame members and roof-sheet nailing strips, and be arranged to confine the posts of a car end frame, and possess suitable means for attachment to said posts.

Another object is to so shape the end plate 40 that it will conform to the pitch of the roof and be adapted to embrace the aforementioned nailing strips and to contact with the external faces of the end and corner posts 45 of a car end frame, irrespective of the disposition of such faces, and also bear a usual relation to the end sheathing.

Other advantages not enumerated, but becoming apparent from the following disclosure, are obviously a part of the present invention, and are to be regarded as coming 50 within its scope.

Referring to the drawings, 1 indicates the web of a channel-shaped end plate, prefer- 55 ably pressed from a single sheet of metal

and shown as extending from one side to the other of the car and having preferably an anticinal upper edge, though the latter may be arched or be otherwise shaped, said upper edge being outlined by an outwardly projecting paralleling upper flange 2, which is relatively narrow and of substantially uniform width throughout its length.

Usually the outstanding lower flange 3 of the end plate is in general wider than the upper flange 2, and said width is regulated in accordance with the characteristics of the car end framing. When the several end posts 4 of the car end framing, here represented as Z-bars, are of different cross-sectional dimensions and are so arranged that with the angle corner posts 5 the inner faces of all of said posts are in the same vertical plane to present attachment surfaces for an inside sheathing 6, the outer faces of said end posts 4 and corner posts 5 occupy different vertical planes. Under these conditions, said lower flange 3 of the end plate is widest in its central portion and diminishes in width as it progresses toward the ends of said plate. Lower flange 3 is provided with an integral depending apron 7, bent downwardly from said lower flange and lying in a path parallel to the contour of the outer edge thereof. Said apron 7 confines the upper extremities of the end and corner posts 4 and 5 respectively, and constitutes a means of attachment thereto, the outwardly presented flanges of said posts being adapted to be engaged by the apron, which is riveted or otherwise secured to said flanges.

In paralleling the directions of tapering of lower flange 3, the apron 7, coincidentally with the terminals of flange 3, merge with the web 1 of the end plate, preferably near the opposite ends thereof, and said apron gradually increases in vertical width from the center of the end plate also to the ends thereof. As a result of the convergence of the ends of the lower flange 3 and the apron 7 to the plane of the vertical web 1 and the increased vertical width of the apron extremities, very substantial end attachment edges 8 for connection to the corner posts 5 are given to the end plate, the riveting areas being materially increased.

The angle formed by the under surface of upper flange 2 and the outer face of web 1 is adapted to receive the nailing strips 9,

which may be secured in any suitable manner to said web 1 or flange 2, or both. By preference, the diminishing opposite end portions of lower flange 3 of the end plate 5 are deflected downwardly, unobstructed passages for the continuation of the nailing strips 9 toward the ends of the end plate being thus provided between upper and lower flanges 2 and 3. When, however, the 10 apex of the anticinal upper flange 2 is at a sufficient height above lower flange 3, said latter flange need not be deflected to accommodate the nailing strips. Carried by web 1, on the inner face thereof, are brackets 10 15 for supporting the end portions of the ridge pole 11 and purlins 12 of the roof frame of the car. Said brackets are shown as comprising short lengths of commercial angles, but it is clear that chairs and hangers 20 of various types may be substituted, and that where the roof members are constructed of steel, gussets, connection plates or the like, may replace the angles shown in the drawings, and equally well perform the 25 same functions.

In Fig. 4 a roof sheet is shown in dot and dash lines at 14, and the manner in which it is related to the nailing strips 9 is clearly indicated in said figure. While the side 30 plates 13, represented as Z-bars, are shown as being directly secured to the corner posts 5, they are not restricted to this form, and in some arrangements the end plate may be further flanged and secured to the side 35 plates.

It is apparent that I have devised an end plate of simple form that may easily be constructed from a single piece of material by a simple method, as by pressing it into 40 its final shape. That the cost of production may be kept low is evident, while the contour derived permits of the end plate serving its ordinary and special purposes, as hereinbefore set forth.

45 What I claim is:

1. An end plate for cars having a channel-shaped cross section and comprising a web portion, an upper flange of substantially uniform width, a lower flange and an 50 apron depending therefrom.

2. An end plate for cars having a channel-shaped cross section and comprising a web portion, a flange paralleling the upper edge thereof, a lower flange tapering from 55 its central portion toward its ends and an apron depending from said lower flange, both said lower flange and apron merging with said web portion.

3. An end plate for cars having a channel-shaped cross section and comprising a 60

web portion, a flange of uniform width paralleling the upper edge thereof, a lower flange tapering from its central portion toward its ends, an apron depending from said lower flange, both said lower flange 65 and apron merging with said web portion, and portions for attachment to corner posts of a car frame.

4. An end plate for cars having a channel-shaped cross section and comprising a 70 web portion, a flange of uniform width paralleling the upper edge thereof, a lower flange tapering from its center toward its ends, an apron depending from said lower flange and increasing in width from its central portion toward its ends, both said 75 lower flange and apron merging with said web portion.

5. An end plate for cars comprising a web portion, outstanding upper and lower 80 flanges, the latter tapering toward its opposite ends and being provided with a depending apron increasing in width as it progresses outwardly, both said lower flange and apron merging with said web portion, 85 and the end portions of said lower flange being deflected to be spaced from and parallel to said upper flange.

6. An end plate for cars having a channel-shaped cross section and comprising a 90 web portion and an upper flange arranged to receive nailing strips, a lower flange adapted to extend over the end posts of a car end frame, and an apron depending from said lower flange adapted to be connected to said end posts and to corner posts, 95 said lower flange and apron merging with said web portion and being shaped to cause the apron to contact with and lap all of said posts.

7. An end plate for cars comprising a web portion and an upper flange arranged to receive nailing strips, roof member-supporting devices secured to said web portion, a lower flange adapted to extend over car 100 frame end posts having outer faces in different planes, and an apron depending from said lower flange increasing in width from its central portion toward its opposite ends and adapted to contact with the 110 outer faces of said end posts and with corner posts, said lower flange and apron merging with the end portions of said web to lie in the same plane therewith.

In witness whereof I have hereunto set 115 my hand in the presence of two witnesses.

JACOB H. WEISBROD.
